ABSTRACT

Disclosed herein is a structural tubing assembly such as a fence or gate in which one tubular member is joined to a second tubular member by (1) cutting an elongated opening in the second member, (2) cutting opposing slots in the end of the first member thus forming two locking tabs, (3) inserting the tabs through the opening in the second member, and (4) spreading the tabs, thus securely and rigidly locking the first tubular member to the second tubular member. Preferably, the end of the first tubular member is partially flattened to conform to the shape of the elongated opening in the second member prior to cutting the two opposing slots to form the locking tabs. Optionally, a reinforcing insert such as a tube of proper size is pressed into the opening between the spread tabs to strengthen the connection.

STRUCTURAL TUBE ASSEMBLY

PRIOR APPLICATIONS

This application is a Continuation-in-Part of U.S. Pat. application Ser. No. 120,107, filed Mar. 2, 1971 now abandoned, su

BACKGROUND OF THE INVENTION

Tubing assemblies are constructed for many purposes such as fences, gates, antenna towers, pre-fab kennels, scaffolding, swing supports, and the like. One of the major use areas relates to the construction of fences and related fixtures. Essentially tubing assemblies for whatever purpose they might be used have in common the fact that they comprise a plurality of tubular members which are connected to form the desired structure. Such connections must be strong and substantially rigid in order to impart structural integrity to the completed unit. In the past, the most accepted method of making such connections was to butt one member against another and weld them together. This is time consuming and does not adapt well to rapid production. It also required that the work be performed at the factory where the necessary welding equipment is located, which greatly limited the amount of assembly that could be done at the construction site.

SUMMARY OF THE INVENTION

The present invention provides a wide variety of tubing assemblies in which a first tubular member is joined to a second tubular member by providing an opening in the wall of the second tubular member through which the end of the first tubular member extends. The end of the first member is generally flattened to resemble the shape of the opening in the second member and slots are cut in the end of the first member to separate the two flattened surfaces into two locking tabs which extend into the opening in the second member and are spread to substantially conform to the contour of the inside surface of the second tubular member, thus locking the members securely and rigidly together. The joint can be strengthened by providing an insert which is pressed between the spread locking tabs, thus holding them securely in place.

BRIEF DESCRIPTION OF THE DRAWINGS

FIG. 1 shows a first tubular member about to be inserted in an opening of a second tubular member.

FIG. 2 shows the completed connection.

FIG. 3 is a partial cross-section of FIG. 1 taken at A—A.

FIG. 4 is a partial cross-section of FIG. 2 taken at B—B.

FIG. 5 shows a completed gate assembly made according to this invention.

FIG. 6 is a partial cross-section similar to FIG. 4 except showing in cross-section a tubular reinforcing insert in place.

FIG. 7 is a cross-section of FIG. 4 taken at C—C.

FIG. 8 is a tubular assembly having multiple rectangular units sharing common tubular members.

FIG. 9 is a cross-section of a tubing connection in FIG. 8 taken at D—D.

DESCRIPTION OF PREFERRED EMBODIMENTS

FIGS. 1 and 3 show tubular members ready to form the connection of this invention. First tubular member

1 has opposing portions of its side wall flattened 2 such that its cross-section conforms substantially to elongated opening 3 is second tubular member 4. Two opposing slots or recesses 5 are cut in tube 1 in a manner such that flattened portions 2 are separated into locking tabs 6 and 7.

FIGS. 2 and 4 show the completed connection. Tabs 6 and 7 extend through longitudinally elongated opening 3 of member 4 and are spread such that they substantially conform to the inside contour 8 of second tubular member 4 firmly locking the tubular members together without the need of welding or of the use of screws, bolts, brackets, locking pins, and the like.

FIG. 5 shows a gate constructed according to the present invention. Vertical members 10 and 11 correspond to tubular member 4 and are provided with an elongated opening 3 in proximity to the top and bottom. The ends of horizontal members 12 and 13 are flattened to provide a slip-fit into opening 3 and are slotted to provide two locking tabs 6 and 7.

A facile method of assembling the gate is to insert the pre-formed ends of members 12 and 13 into the elongated openings in members 10 and 11. At this stage the assembly can be held in a fixture. Then, as shown by phantom lines in FIG. 7, a tapered pin 15 is driven through the ends 16, 17, 18 and 19 of members 10 and 11 in between tabs 6 and 7, thus spreading the tabs and forcing them into locking position against the inner surface 8 of members 10 and 11.

The gate frame is then provided with fencing 20 which is attached to members 10, 11, 12 and 13. For installation, the completed gate is provided with hinges 21 and 22 and latch 23.

The rest of the fence can be assembled in the same manner as the gate.

As shown in FIG. 5, the connected tubular members are at right angles with each other, but this is not necessary as the connection can be formed over a wide angle range.

In another embodiment of my invention, illustrated in FIG. 6, a reinforcing insert 60 is press-fit into the space between spread locking tabs 6 and 7 in second tube member 4. Insert 60 as shown is a tubular insert but may be any suitable material such as wood or plastic pin. Also useful is a segment of split tubing which is compressed for insertion and then allowed to expand against tabs 6 and 7.

In another embodiment the reinforcing insert 60 is a swedged end of third tubular member of the tubing assembly. By "swedged," I mean that the end of the tubular member is reduced in diameter by known means such as forcing the tube into a die having a circular opening of smaller diameter than that of the tubular member. According to this embodiment, more complex tubular structures may be assembled without use of welding or brackets, although such other attachment methods may be used in conjunction with my method. This embodiment of my invention permits construction of such things as pre-fab fence units containing more than one rectangular frame. It is also useful in construction of such assemblies as TV antenna towers made of three or four long vertical tubes each of which is cross-braced to another of the vertical tubes. The lower end of upright tubular members are swedged and inserted into the upper end of another upright tubular member forming long vertical tubes and at the same time reinforcing the connection of the cross-brace members

which are connected to the upright tubular members in accordance with this invention.

FIG. 8 shows a typical fence section suitable for use in assembling a dog kennel. It is comprised of lower upright tubular members 30 and 31 and horizontal members 32 and 33 which together form a rectangular frame. Ends 34 and 35 of tubular member 33 are flattened and slotted to form opposed locking tabs and fit into an elongated opening in the top of upright members 30 and 31. The locking tabs are spread to form connections of this invention. One end 36 of member 32 is also flattened, slotted, and inserted into an elongated opening at the lower end of upright member 30 wherein it is spread to form a connection of this invention. The lower end 37 of upright member 31 is flattened, slotted, and fit into an elongated opening near the end of member 32 wherein it is spread to form a connection of this invention. A second rectangular frame is constructed by inserting the lower swaged ends 38 and 39 of upright members 40 and 41 in between the spread locking tabs inside the upper end of members 30 and 31. This should be a press-fit to form a secure joint. The joint formed is further illustrated in FIG. 9. Phantom lines show swaged end 39 of member 41 inserted in between the locking tabs 6 and 7 of member 35. This forms a secure joint of three tubular members.

Upper horizontal tubular member 42 is flattened and slotted at end 43 to form opposed locking tabs as 6 and 7 in FIG. 3. These are inserted in an elongated opening in the side wall of member 40 near its upper end. The locking tabs are spread by driving in a tapered rod and a tubular insert is pressed in between the spread locking tabs to reinforce the joint as shown in FIG. 6.

At the opposite end 44 of member 42 an elongated opening is provided which receives the locking tabs formed by flattening and slotting the upper end of member 41. This completes a second rectangular frame sharing common tubular member 33 with the first rectangular frame.

An opening suitable for the installation of a gate is next provided by inserting the swaged ends 45 and 46 of horizontal members 50 and 51 in between the spread locking tabs of members 41 and 31 within tubular members 42 and 32 forming a reinforced connection as illustrated in FIG. 9. The opposite end 52 and 53 of members 50 and 51 are flattened and slotted to form locking tabs which are inserted in elongated openings in the side wall and near the ends of tubular member 54. These locking tabs are spread inside member 54. Tubular reinforcing inserts are pressed in between the spread locking tabs to form a secure rigid joint as shown in FIG. 6.

From the foregoing description, it can be seen that a great many tubular frame assemblies can be fabricated using the connection provided by this invention. The number of such assemblies is limited only by the imagination and ingenuity of the fabricator.

I claim:

1. A structural tubing assembly comprising at least one substantially rigid connection of a first tubular member to a second tubular member, said connection comprising (A) an opening in the wall of said second tubular member, the width of said opening being less than the inside diameter of said second tubular member, and (B) opposing longitudinal slots in the end of said first tubular member such that the wall between

said slots form two locking tabs, said tabs being positioned through said opening and inside of said second tubular member and shaped to abruptly diverge and converge to substantially conform to and tightly contact the inside surface of said second tubular member to prevent angular and lateral distortion thereof forming a substantially rigid connection of said first tubular member to said second tubular member.

2. A tubing assembly of claim 1 wherein said opening 10 in the wall of said second tubular member is longitudinally elongated and the opposing side walls of said first tubular member at the location at which it extends through said opening in said second tubular member are flattened such that the cross-section of said first tubular member at said location substantially conforms with said longitudinally elongated opening in said second tubular member.

3. A tubing assembly of claim 1 further characterized by having a cylindrical reinforcing insert tightly fitted 20 between said two locking tabs, said insert conforming with the inside contour of said two locking tabs thereby holding said tabs tightly against the inside surface of said second tubular member.

4. A tubing assembly of claim 3 wherein said reinforcing insert is an end of a third tubular member of said structural tubing assembly, said end having a reduced outside diameter to conform with the inside contour of said two locking tabs.

5. A tubing assembly of claim 1 wherein said first and 30 said second tubular members have a substantially circular cross-section.

6. A tubing assembly of claim 5 wherein said opening in the wall of said second tubular member is longitudinally elongated and the opposing side walls of said first tubular member at the location at which it extends through said opening in said second tubular member are flattened such that the cross-section of said first tubular member at said location substantially conforms with said longitudinally elongated opening in said second tubular member.

7. A tubing assembly of claim 6 further characterized by having a cylindrical reinforcing insert tightly fitted between said two locking tabs, said insert conforming with the inside contour of said two locking tabs thereby holding said tabs tightly against the inside surface of said second tubular member.

8. A tubing assembly of claim 7 wherein said reinforcing insert is a tubular member tightly fit between said two locking tabs.

9. A tubing assembly of claim 8 wherein said tubular member is an end of a third tubular member of said structural tubing assembly, said end having a reduced outside diameter to conform with the inside contour of said two locking tabs.

10. A substantially rectangular tubular frame assembly comprising four tubular members, each of said members connected at both ends to another of said four tubular members to form a substantially rectangular frame, each of said connections comprising (A) a longitudinally elongated opening in one of the connected members, the width of said opening being less than the inside diameter of said one of the connected members, and (B) opposing longitudinal slots in the end of the other of said connected members such that the wall between said slots forms two locking tabs, said tabs being inserted through said elongated opening and abruptly diverging and converging to substantially con-

form to the inside surface of said one of the connected members forming a substantially rigid rectangular frame.

11. A tubular frame assembly of claim 10 useful as a gate or fence section wherein fencing is positioned in the rectangular area formed by said four tubular members and is attached to said members.

12. A tubular frame assembly of claim 10 further characterized by having a cylindrical reinforcing insert tightly fitted between said two locking tabs, said insert conforming with the inside contour of said two locking

tabs thereby holding said tabs tightly against the inside surface of said one of the connected members.

13. A tubular frame assembly of claim 12 wherein at least one of said reinforcing inserts is an end of another tubular member which forms one side of an adjoining tubular frame assembly, said adjoining tubular frame assembly sharing a common tubular member with said tubular frame assembly of claim 12, said end having a reduced outside diameter to conform with the inside contour of said two locking tabs.
